UNITED STATES PATENT OFFICE.

ALFRED COTTON AND LOUIE F. KOELLNER, OF HARTFORD, CONNECTICUT.

SHEET-METAL WHEEL.

1,352,723.

Specification of Letters Patent. Patented Sept. 14, 1920.

Application filed July 23, 1919. Serial No. 312,731.

To all whom it may concern:

Be it known that we, ALFRED COTTON and LOUIE F. KOELLNER, citizens of the United States, and residents of Hartford, in the county of Hartford and State of Connecticut, have invented certain new and useful Improvements in Sheet-Metal Wheels, of which the following is a specification.

This invention relates to improvements in vehicle wheels, and has for its general object the provision of a light and strong metallic wheel having the hub and the rim thereof connected by a sheet metal web so constructed as to adapt the wheel to sustain heavy loads and to effectively resist torsional and lateral strains.

Another object of the invention is to provide a light but exceedingly rigid hub and rim connecting member or web for metallic wheels of the disk type which may be readily formed of light sheet metal.

A further object of the invention is to provide a connecting web or member for the hub and rim of a wheel formed by folding a blank of metallic stock to produce a web of general disk form having radial corrugations of considerable depth at the center of the web, said corrugations increasing in width and decreasing in depth toward the perimeter of the web, the axial depth of the corrugations at the hub being governed by the length of the portion of the hub available for connection with the web.

In the drawings; Figure 1 is a side elevation showing the outer face of one form of wheel, embodying the invention, a portion of the outer member of the sheet metal web being broken away;

Fig. 2 a transverse sectional view thereof; Fig. 3 a side elevation showing the inner face of the wheel;

Fig. 4 a fragmentary transverse section of the wheel on an enlarged scale;

Fig. 5 a fragmentary section on the line V—V of Fig. 2;

Fig. 6 a fragmentary section on the line VI—VI of Fig. 2;

Figs. 7 and 8 fragmentary sections on the line VIII—VIII of Fig. 2, the outer member only of the web being shown in Fig. 7;

Figs. 9 and 10 detail vertical transverse sections on an enlarged scale of the inner and outer members, respectively, of the form of web shown in Figs. 1 to 8;

Fig. 11 a vertical section of a slightly modified form of inner web member;

Figs. 12 and 13 side elevations showing

the opposite faces of a modified construction of web having integral inner and outer members;

Fig. 14 a vertical transverse section of the form of web shown in Figs. 12 and 13.

Referring to the various parts by numerals, 1 designates the hub of the wheel, 2 and 3 the two sections of a demountable rim, 60 and 4 a suitable pneumatic tire. The hub is preferably made of cast steel and the rim sections of rolled steel. The hub and rim are connected by a sheet metal web structure comprising an inner disk-like portion 5, an 65 outer disk-like portion 6, and a sheet metal bearing sleeve or tubular member 7 extending through an axial opening in the web and welded adjacent its ends to the disk-like portion 6 and a driving spider 13 herein- 70 after described.

The disk-like portion 5 of the web is corrugated along substantially radial lines, said corrugations increasing in width and decreasing in depth toward the perimeter of 80 the disk. The disk-like portion 5 of the web is of general conoidal form, the summits of the ridges formed by the corrugations at the inner face of the wheel lying in substantially the same vertical plane throughout the 85 length of the ridges. The outer disk-like portion 6 of the web is dished and the inner face thereof engages the summits of the ridges formed at the outer side of the web portion 5 by the corrugations throughout 90 the length of said ridges, and the portions or members 5 and 6 of the web are welded together along the summits of said ridges. The outer member or portion 6 of the web is formed at its outer edge or perimeter with 95 segmental laterally extending portions or lugs 8 fitting in the grooves formed in the outer face of the member or portion 5 of the web by the corrugations, and said members 5 and 6 are welded together at the 100 perimeter of the web along their abutting edges. The welded members 5 and 6 and sleeve 7 thus form a skeleton sheet metal conoidal rim support or web.

A series of blocks 9 are secured adjacent 105 the perimeter of the web at the inner side of the member 5, and a series of spacing members 10 are secured between the members 5 and 6 in register with blocks 9. The section 2 of the divided rim is fixed to the 110 sheet metal web by rivets 22 which pass through blocks 9, disk-like member 5, spacing members 10, disk-like member 6 and the inwardly extending flange on rim section 2.

The rim section 3 is detachably held in place by bolts 11 which pass through the inwardly extending flanges on the rim sections and through apertures in the members 5 and 6 of the web and spacing members 10, and are threaded at their inner ends into the blocks 9. A metallic stiffening ring 12 surrounds the outer end of sleeve 7 and is welded to the outer face of the member 6 of the web.

10 A sheet metal driving spider 13 surrounds the inner end of sleeve 7 and is welded to said sleeve. The spider 13 is formed with radially extending fingers bent laterally toward the web and engaging in the grooves 15 formed in the inner face of the web by the corrugations. The spider 13 is welded to disk-like member 5 of the web along the edges of the fingers of the spider. A metallic driving ring 14 is welded to the face 20 of the spider and surrounds the inner end of sleeve 7 between the spider 13 and a flange 15 formed on hub 1. To form a driving connection between the ring 14 and the hub 1, the ring 14 is provided with apertures 25 adapted to receive the heads of a series of bolts 16 passing through the flange 15 on the hub. The bolts 16 may be also utilized to secure a brake drum 17 to the hub. The entire rim-supporting structure, including 30 the disk-like members 5 and 6, the spider, 13, rings 12 and 14, and tube 7, is removably held on the hub by a hub cap 18 with the driving ring interlocked with the heads of bolts 16. The hub cap 18 is formed with a 35 beveled flange embracing the stiffening ring 12 and is detachably held to the outer end of the hub by bolts 19 which are threaded into the end of the hub. A suitable dust cap 20 is threaded on the hub cap. The 40 member 5 may be cut away as shown at 21 and 23 to reduce the weight of the web structure, if desired.

In Fig. 11 a slightly modified form of corrugated web member or supporting element is shown, said web member 5^a being of substantially double frusto-conoidal form, the summits of the ridges formed by the corrugations at opposite faces of the member projecting laterally equal distances beyond 50 the plane of the perimeter of the member. The web member 5^a is adapted for attachment to a dished web member similar to web member 6 in the construction heretofore described to form a hub and rim connecting 55 web. The web so constructed may be associated with a hub and rim in the manner shown in Figs. 1 to 10, or in any other suitable manner.

In Figs. 12, 13 and 14 still another form 60 of web is shown. In this construction the inner and outer members of the web are integral, the web being formed by folding a single piece of material. The outer portion 65 or member 24 of the web is provided with a central aperture 25 and is pressed into

dished form with a channel 24^a therein adjacent the perimeter of the web. The inner portion or member 26 of the web is provided with a central aperture 27 registering with aperture 25 in the member 24, and said inner 70 member 26 is formed with radial corrugations increasing in width and decreasing in depth from the aperture 27 to the perimeter of the web. A stiffening or reinforcing ring 28 of rolled steel is confined in the channel 75 24^a, the inner face of said ring being flush with the inner face of member 24. Said ring 28 is welded, brazed, or otherwise secured to member 24, and the members 24 and 26 are welded together along the summits of the ridges formed by the corrugations at the outer side of member 26. A sheet metal tubular bearing member, similar to member 7 in the construction shown in Figs. 1 to 10, may be passed through the 80 apertures 25 and 27 and welded to members 24 and 26 and the web may be secured on a hub in the manner shown in said previously described construction. A rim such as that shown in the previously described construction 85 may be supported on the web, the member 2 of the rim being permanently secured to the web by rivets passing through apertures 29 in the web members and ring 28 and through the inwardly extending flange 90 on the rim member. It will be obvious that, if desired, the construction shown in Figs. 12 to 14 may be readily formed so that the summits of the ridges formed by the corrugations at the inner side of the web would 100 lie in the plane of the perimeter of the web, as in the construction shown in Figs. 1 to 10.

It will be obvious that various other forms of hubs, rims, and tires may be associated with either of the sheet metal web structures 105 above described, and that either of the web structures may be secured to the hub and rim or felly members of a wheel in various ways. It will also be obvious that the several welded parts may be secured together 110 in other ways such as riveting or brazing.

A feature of importance resides in the fact that by the construction shown a very rigid skeleton supporting web for the wheel rim is provided which is so constructed, and 115 so connected with the rim and hub, that entrance of dirt within the wheel structure is impossible. A further important feature of the invention resides in the fact that the web is so formed as to provide a strong, but 120 light, beam-like structure well adapted to withstand heavy, lateral, torsional and vertical strains, the corrugations being so shaped that the web comprises in effect a series of radially extending connected beams or columns of maximum width at the hub of the wheel.

What we claim is:

1. A vehicle wheel comprising an inner sheet metal web member having radially 130

extending corrugations increasing in width and decreasing in depth toward the perimeter of the member, an outer sheet metal web member, the inner face of which is engaged along radial lines by the outer face of the inner member along the summits of the ridges formed by the corrugations at the outer side of the inner member, a hub extending through the web members centrally thereof, and a rim supported by the web members.

2. A vehicle wheel comprising an inner sheet metal disk-like web member having radially extending corrugations increasing in width and decreasing in depth toward the perimeter thereof, an outer sheet metal disk-like web member secured to the inner member along the summits of the ridges formed by the corrugations at the outer side of the inner member, a hub extending through the web members centrally thereof, a driving spider having radially extending fingers held to the inner side of the inner member, a driving connection between the hub and spider, and a rim supported by the web members.

3. A vehicle wheel comprising an inner sheet metal disk-like web member having radially extending corrugations increasing in width and decreasing in depth toward the perimeter thereof, an outer sheet metal disk-like web member secured to the inner member and engaging the inner member along the summits of the ridges formed by the corrugations at the outer side of the inner member, a hub extending through the web members centrally thereof, a sheet metal spider secured to the inner member and having radially extending fingers bent laterally at their outer end into the grooves formed in the inner face of the inner member by said corrugations, a driving connection between the hub and spider, and a rim supported by the web members.

4. A vehicle wheel comprising an inner sheet metal disk-like member having radially extending corrugations increasing in width and decreasing in depth toward the perimeter thereof, an outer sheet metal disk-like member of dished form welded to the outer face of the inner member along the summits of the corrugations formed in the inner member, a hub extending through the members centrally thereof, and a rim supported by the members.

5. A vehicle wheel comprising an inner sheet metal member having radially extending corrugations increasing in width and decreasing in depth toward the perimeter thereof, an outer sheet metal member secured to the outer face of the inner member along the summits of the ridges formed by the corrugations in the inner member, a sheet metal spider having radially extending arms bent laterally into the grooves

formed in the inner face of the inner member by the corrugations, said spider being secured along the edges of the arms to the inner member, a tubular sheet metal member extending through registering axial apertures in said inner and outer members and spider and secured at its ends to the outer member and the spider, a hub extending through the tubular member, and a rim secured to the inner and outer members. 70 75

6. A vehicle wheel comprising an inner sheet metal disk-like web member having radially extending corrugations increasing in width and decreasing in depth toward the perimeter thereof, an outer sheet metal disk-like web member secured to the inner web member along the summits of the ridges formed by the corrugations in the inner web member, a sheet metal spider having radially extending arms bent laterally into the grooves formed in the inner face of the inner web member by the corrugations, said spider being secured along the edges of the arms to the inner web member, a tubular sheet metal member extending through the web members and spider and secured at its ends to the outer web-member and the spider, a hub extending through the tubular member, a driving ring surrounding the hub and secured to the spider, a driving connection between the ring and the hub, and a rim supported by the web members. 80 85 90 95

7. A vehicle wheel comprising two abutting sheet metal disk-like web members secured in fixed relation and having registering central apertures therein, one of said web members being provided with radially extending corrugations increasing in width and decreasing in depth toward the perimeter thereof, a tubular sheet metal member extending through the registering central apertures in the web members and held to rotate with said web members, a hub extending through said tubular member, and means for securing the web members and tubular member on the hub to rotate therewith. 100 105 110

8. A hub and rim connecting element for wheels of the disk type comprising two rigidly connected sheet metal disk-like portions having registering axial openings therein, one of said disk-like portions being dished and the other being formed with radial corrugations increasing in width and decreasing in depth from the opening therein toward the perimeter thereof, the summits of the ridges at one side of the corrugated portion of said element touching the concave face of the dished portion of the element. 115 120 125

In testimony whereof we hereunto affix our signatures this 21st day of July 1919.

ALFRED COTTON.
LOUIE F. KOELLNER.
